(57) CLAIM

The ornamental design for a hearth, as shown and described.

DESCRIPTION

The broken line portions in Figure 1.7 form no part of the claimed design.
